UNITED STATES PATENT OFFICE

164,492

COMBINED GRAVE COVER AND MARKER

George Elgin Harvey, Vancouver,
British Columbia, Canada

Application April 10, 1950, Serial No. 9,108

Term of patent 3½ years

(Cl. D79—2)

To all whom it may concern:

Be it known that I, George Elgin Harvey, a citizen of Canada, residing at Vancouver, British Columbia, Canada, have invented a new, original, and ornamental Design for Combined Grave Cover and Marker, of which the following is a specification, reference being had to the accompanying drawing, forming part hereof.

The figure is a perspective view of a combined grave cover and marker, showing my new design.

I claim:

The ornamental design for a combined grave cover and marker, as shown.

GEORGE ELGIN HARVEY.
